(57) **CLAIM**

The ornamental design for an earphone, substantially as shown and described.

DESCRIPTION

FIG. 1 is a front perspective view of an earphone showing our new design;

FIG. 2 is a rear perspective view of the earphone in FIG. 1; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings represent the portions of the earphone that form no part of the claimed design.

1 Claim, 8 Drawing Sheets
